FOUNTAIN PEN

Filed Oct. 21, 1932

UNITED STATES PATENT OFFICE

1,987,646

FOUNTAIN PEN

Alfred H. Swan, Los Angeles, Calif.

Application October 21, 1932, Serial No. 638,960

15 Claims. (Cl. 120—47)

My invention relates broadly to fountain pens and more particularly to an improved construction of self filling fountain pen.

One of the objects of my invention is to provide an improved construction of self filling fountain pen which is efficient in operation and inexpensive in manufacture and assembly on a quantity production basis.

Another object of my invention is to provide a construction of self filling fountain pen having a large capacity reservoir for ink, and adapted to be conveniently filled and arranged for the uniform feeding of ink to the pen point.

A further object of my invention is to provide a construction of multiple section fountain pen having means for preventing leakage of ink from the pen while allowing normal filling and writing operations.

A still further object of my invention is to provide a construction of telescoping barrels for fountain pens having a multiplicity of lubricating seals for preventing leakage and capillary passage of ink, at the same time substantially lubricating the relatively movable barrels.

Another object of my invention is to provide a construction of fountain pen having a central reservoir adapted to be filled by a suction operation effected by movement of one of a plurality of telescopic sections, with means for releasing entrapped air through a central tube extending through the reservoir to the feed section of the pen.

Still another object of my invention is to provide a system of valves for a multiple section pen operative to effect filling and feeding operation of the pen without leakage of ink and insuring the proper egress of air.

Other and further objects of my invention reside in the construction of ink filling and feeding mechanism for fountain pens as set forth more fully in the specification hereinafter following by reference to the accompanying drawing, in which:

Figure 1 is a vertical cross-sectional view taken through the fountain pen construction of my invention showing the position of the parts during a filling operation of the pen; Fig. 2 is a cross-sectional view taken through the pen illustrated in Fig. 1 and showing the position of the parts during a writing operation of the pen; Fig. 3 is a cross-sectional view taken through the drag employed in the fountain pen structure, the view being taken on line 3—3 of Fig. 1; Fig. 4 is a cross-sectional view through the pen on line 4—4 of Fig. 1; Fig. 5 is a cross-sectional view taken

through the pen on line 5—5 of Fig. 1; Fig. 6 is a fragmentary cross-sectional view of a modified form of drag structure employed in the pen of my construction; and Fig. 7 is a perspective view of a still further modified form of drag construction.

Referring particularly to the drawing, reference character 1 designates the outer barrel of the fountain pen. The lower end of the outer barrel is internally screw threaded at 1a. The upper end of the outer barrel 1 is internally screw threaded at 1b and has an annular abutment 1c riveted thereto as indicated at 1d immediately below the internal screw threads 1b. Reference character 2 designates the inner barrel which forms the outer wall of the ink reservoir 5. The intermediate barrel 3 is longitudinally slidable in the space between the outer barrel 1 and the inner barrel 2. The intermediate barrel 3 telescopes or slides with respect to the outer barrel 1 and inner barrel 2. The solid lower portion of the fountain pen is designated at 4 and serves to connect the inner and outer barrels. The solid lower portion 4 is externally screw threaded at 4a to receive the internal screw threads 1a on outer barrel 1 thereby maintaining the inner and outer barrels in predetermined spaced relation. The lower end of the barrel 4 is provided with an internally screw threaded bore 16 which receives the threaded member 28 carrying the feed 27 and nib 26. The threaded member 28 is screwed wholly into the lower end of the barrel 4 leaving an annular opening at the end of the barrel which receives the inner screw threaded portion 24 of the cap 23. A channel 29 is provided in the feed 27 for leading the ink to the nib through aperture 30 at the end of the channel 29. The hollow reservoir for holding the ink is represented at 5. The reservoir communicates freely at its lower end with the channel 29 in the feed 27.

The upper end of the telescopically slidable section 3 terminates in a finger grip or cap 6 which is relatively thin walled and hollow to afford maximum capacity in the reservoir 5 for a relatively short barrel. The finger grip 6 is screw threaded as represented at 6a to engage with the internal screw threads 1b on the outer barrel 1. The upper end of the inner barrel 2 has been shown at 10 consisting of a laterally disposed section which is apertured at its center as represented at 10a to receive a tubular member 10b. Pass-

ing through the tubular member 10b, I provide the longitudinally shiftable air pipe 7. It will be noted that the air pipe 7 has an outwardly flanged end 7a at its upper extremity which is adapted 5 to seat against the peripheral edge of the tubular member 10b when the air pipe 7 is shifted to its lowest position. The upper end of the air tube 7 and the tubular member 10b is spaced away from the peripheral edge of the tubular 10 member 10b to provide an annular air vent space 11 when the air tube is moved to its extreme upper position. The movement of the air tube 7 is limited by the abutment of the annular stop 31 with the lower face of the end section 10. 15 However this does not close the air passage through the air vent 11 as the passages 31a in the stop 31 are open and enable air to pass through the air vent 11 when the air tube 7 is in its extreme upper position as will be more fully 20 described hereinafter. The outer surface of the inner barrel 2 is provided with a plurality of annular grooves 8 formed in the barrel. The grooves 8 are filled with paraffin and provide a series of packing and lubricating zones progressively along 25 the length of the inner barrel 2. These successive zones of paraffin provide continuous lubrication for the parts of the pen throughout the useful life of the pen and also serve to provide substantial packing between the movable parts 30 of the pen and prevent capillary seepage of ink along the barrel in the event that any ink should escape from reservoir 5 into the inner portion of the intermediate barrel 2. Paraffin is a solid at all ordinary temperatures and will not wear out 35 so that the pen will not lose suction over its normal period of life.

Reference character 9 designates a drag washer which fits snugly within the upper portion of intermediate barrel 3. The dimensions are such 40 that there is substantial friction between the peripheral edge of drag washer 9 and the interior walls of the intermediate barrel 3. The drag washer has a central aperture 9a therein through which the central lift wire or rod member 12 is secured. The connection between the lift wire or 45 rod member 12 and the drag washer 9 is effected by means of a diametrically extending pin 12a around which the end of the wire 12 is secured. The drag washer 9 is provided with a plurality of 50 spiral slots 9d directly cut in the drag washer for imparting resiliency to the washer and enabling the washer to grip the interior walls of the intermediate barrel 2. The slots 9d are placed in the 55 drag washer 9 by any suitable saw or other tool. The construction of the drag washer may be modified in various ways as has been illustrated in Figs. 6 and 7. In Fig. 6 the drag washer 9 has been shown as having an annular groove in the peripheral edge thereof forming a seat for a gasket 9b which establishes frictional connection 60 with the interior wall of the intermediate barrel 3 as the intermediate barrel 3 is moved vertically. The lift wire or rod 12 is connected with a valve head 13 on the lower end thereof and serves to 65 seal the end of the air tube 7 as illustrated in Fig. 1 when the intermediate barrel 3 is moved vertically. This operation is effected by reason of the frictional engagement between drag washer 9 and the interior wall of the intermediate barrel 3. 70 The drag washer 9 is shifted by frictional engagement with the interior walls of the intermediate barrel 3 to shift the lift wire or rod 12 vertically and seat the valve 13 against the end of the air tube 7. Continued upper movement of the drag washer 9 tends to lift the air tube 7 thereby open-

ing the air vent 11 by shifting the outwardly flared portion 7a of the air tube 7 away from its coacting seat on the tubular member 10b. The filling operation is continued, the air seeping out through passage 31a, in stop 31 through vent 11, and also through the drag washer by way of space 9a or spiral cuts 9d, and into the interior of the intermediate barrel 3. When the filling operation is complete and the down stroke commences the drag washer 9 is frictionally moved by an 10 abrasion of the interior wall of intermediate barrel 3 with the peripheral edge of the drag washer 9 effecting a downward displacement of wire or rod member 12, thereby opening valve 13 at the end of the air tube 7 to permit the escape of air 15 out through the space 14, passage 14a and passage 29, escaping through the eye 30. The drag washer 9 contacts with the upper edge of the flange 7a of air tube 7 forcing the flange against the annular edge portion of the tube 10b and closing air vent 11, thereby preventing air pressure 20 acting upon the upper surface of the ink in the reservoir 5. The ink in feeding to the nib and pen point is free to gravitate from reservoir 5 through spaces 14 and 14a to channel 29 and through the 25 eye 30 to the pen point as heretofore explained.

The multiplicity of paraffin zones insures substantial lubrication between the telescoping intermediate barrel and the inner barrel 2, at the same time providing a tight seal against the capillary seepage of ink. The closing of the air tube by a valve 13 insures against the excessive leakage of ink through the channel 29 and eye 30 of the pen. The arrangement of the stop 31 on the air tube 7 is such that the limit of movement of 35 the air tube 7 is accurately predetermined.

The engagement of the tube 24 of the cap 23 with the internal screw threads 16 at the end of the barrel of the pen insures a tight seal at the end of the pen preventing the leakage of ink 40 while the pen is being carried and also avoids any exterior threading operation on the barrel of the pen. In this way the manufacturing cost is substantially reduced inasmuch as the same screw threads which serve to support the feed 45 assembly through member 28 in the end of the barrel of the pen also serve as the connecting means for the cap on the pen. Threads are undesirable on the barrel of a pen as they directly contact with the fingers. My construction 50 entirely eliminates any exterior threads on the barrel to the increased comfort of the writer.

I have found the pen construction of my invention highly practical and successful in operation, and while I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. In a fountain pen, a multiplicity of concentric sections, one of said sections being longitudinally movable with respect to others of said sections, and means carried by one of said last mentioned sections comprising a multiplicity of annular recesses with waxlike material disposed therein for sealing the said last mentioned section with respect to said longitudinally movable section.

2. A pen having a plurality of concentric cylindrical barrel sections including a stationary section, one of said barrel sections being telescopically movable with respect to others of said barrel

sections, and a plurality of spaced annular recesses in said stationary barrel section, said recesses being filled with waxlike material for establishing a sealed connection between said concentric barrels.

5. In a fountain pen, a multiplicity of concentric cylindrical barrels including a stationary inner cylindrical barrel, one of said barrels being telescopically slideable with respect to others of 10 said barrels, a multiplicity of spaced annular recesses in the stationary inner cylindrical barrel, said recesses being filled with lubricating material for establishing a sealed and lubricated connection between said barrels as said slideable barrel is 15 moved with respect to said stationary barrel.

6. In a fountain pen, a multiplicity of concentric cylindrical barrel sections, one of said barrel sections constituting a reservoir for ink, a feeding head connected with the lower end of said 20 barrel, one of said sections being telescopically slideable with respect to others of said sections, said barrel having a central port in the upper end thereof, an air tube extending through said port and through a portion of said feeding head and being longitudinally displaceable with respect 25 thereto, a drag washer disposed in the upper portion of said telescopically slideable section, a valve in the lower end of said air tube, a connection extending through said air tube from said drag washer to said valve, said drag washer operating under control of the movement of said 30 telescopically movable section for simultaneously controlling the operation of said valve and the movement of said air tube with respect to said 35 port for controlling the filling and writing operations of said pen.

7. In a fountain pen, a barrel, a plurality of concentric cylinders connected with said barrel, one of said cylinders being telescopically slideable with respect to said barrel, an ink feeding head connected with the lower end of said barrel, an air tube extending through a port in the upper end of said barrel and through a portion of said feeding head, a valve disposed at each end of said 40 air tube, and an axially extending rod member controlled by said telescopically movable cylinder for simultaneously controlling the operation of both of said valves for effecting a filling and writing operation of said pen.

8. In a fountain pen, a barrel structure, a multiplicity of concentric cylindrical members connected with said barrel structure, one of said cylindrical members being telescopically slideable with respect to the others of said cylindrical 50 members, an ink feeding head connected with the lower end of said barrel, an air tube extending axially through said barrel, a valve at each end of said air tube, and an axially extending longitudinally movable rod member controlled by the 55 operation of said telescopically slideable cylindrical members for simultaneously controlling the operation of each of said valves for effecting the filling and writing operation of said pen.

9. In a fountain pen, a barrel structure, a multiplicity of cylindrical members connected with said barrel structure, one of said cylindrical members being telescopically slideable with respect to said barrel structure, an ink feeding head in the lower end of said barrel structure, an air feeding 60 tube extending axially through said barrel and longitudinally shiftable in position with respect thereto, an air valve at each end of said air tube, and a longitudinally movable axially extending rod member in said telescopically slideable cylindrical members for alternately opening said

valves for effecting filling and writing operations.

10. In a fountain pen, a barrel structure, an ink feeding head extending from the lower end of said barrel structure, a multiplicity of concentrically disposed cylindrical members connected with said barrel structure, one of said cylindrical members being telescopically slideable with respect to said barrel structure, a drag washer frictionally engaged with the interior surface of said telescopically slideable member, an air tube extending axially through said barrel structure and longitudinally shiftable with respect thereto, an air valve at the lower end of said air tube, an air vent at the upper end of said air tube, and a connection between said drag washer and the air valve at the lower end of said air tube for effecting a closing and opening operation of both said air valve and said air vent under control of frictional force imparted to said drag washer as said telescopically slideable member is operated with respect to said barrel structure for controlling the filling and feeding operation of said pen.

11. In a fountain pen, a barrel structure, a pair of concentrically disposed cylindrical members connected with said barrel structure, one of said cylindrical members being telescopically slideable with respect to said barrel structure, an ink feeding head connected with the lower end of said barrel structure, the upper end of said barrel structure having a central port therein, an air tube extending through said central port, a valve extending through the lower end of said air tube, said air tube having a portion at its upper extremity coacting with said port for controlling the passage of air from said barrel structure into said telescopically movable cylindrical member, a drag washer operative within the interior of the upper portion of said telescopically slideable cylindrical member, a connection from said drag washer to the valve at the lower end of said air tube, a limiting abutment carried by said air tube adjacent the upper end of said barrel for limiting the longitudinal movement of said air tube, said drag washer operating to simultaneously control the operation of the valves at each end of said air tube for controlling the filling and feeding operations of said pen.

12. In a fountain pen, a barrel structure, a multiplicity of concentrically disposed cylindrical members, one of said cylindrical members being telescopically slideable with respect to said barrel structure, an ink feeding head in the end of said barrel structure, a multiplicity of valves in said pen for controlling the filling and feeding operations of said pen, and a drag washer connected with one of said valves and operative interiorly of one of said cylindrical members, said drag washer having a friction engaging peripheral surface establishing connection with the interior wall of said telescopically slideable cylindrical member.

13. In a fountain pen of the class described, a barrel structure, a plurality of concentrically disposed cylindrical members connected with said barrel structure, one of said cylindrical members being telescopically slideable with respect to said barrel structure, an ink feeding head carried by one end of said barrel structure, a pair of valve systems for controlling the filling and feeding operations of said pen, and a drag washer engageable with the interior wall of said telescopically slideable member for controlling the operation of said valve systems, said drag washer comprising a flat disc extending laterally of said telescopically slideable cylindrical member and having a

multiplicity of spirally disposed slots therein for imparting resiliency to said drag washer.

12. In a fountain pen of the class described, a barrel structure, a plurality of concentrically disposed cylindrical members connected with said barrel structure, one of said cylindrical members being telescopically slideable with respect to said barrel structure, an ink feeding head carried by one end of said barrel structure, a pair of valve systems for controlling the filling and feeding operations of said pen, and a drag washer engageable with the interior wall of said telescopically slideable member for controlling the operation of said valve systems, said drag washer comprising a flat disc disposed laterally of said telescopically slideable cylindrical member and having an annular gasket surrounding the peripheral edge thereof and frictionally engaging the interior walls of said telescopically slideable cylindrical member.

13. In a fountain pen, a barrel structure, a multiplicity of cylindrical members connected with said barrel structure, one of said cylindrical members being telescopically slideable with respect to said barrel structure, an ink feeding head connected with the lower end of said barrel structure, said barrel structure having the upper end thereof centrally ported, a valve seat in the centrally ported end of said barrel structure, an air feeding tube extending axially of said barrel structure between said ink feeding head and through the ported upper end of the barrel structure, the air tube having an annular flange thereon adapted to seat against the valve seat in the end of said barrel structure, the drag washer operative in the interior upper portion of said telescopically slideable member, and a connection between said drag washer extending through said

air tube and connected with the valve in the lower end of the air tube for controlling the operation of said valve and the venting of air between the upper end of said air tube and the port in the end of said barrel structure for controlling the feeding and writing operations of said pen.

14. In a fountain pen, a barrel structure, an ink feeding head carried by the lower end of said barrel structure, a multiplicity of concentric cylindrical members connected with said barrel structure, one of said cylindrical members being telescopically slideable with respect to said barrel structure, an air feeding tube extending axially through said barrel structure, a valve at each end of said air feeding tube for controlling the filling and writing operations of said pen, and a longitudinally movable axially extending rod member operative automatically under control of the sliding movement of said telescopically slideable member for simultaneously controlling the operation of both of said valves.

15. In a fountain pen, a barrel structure, an ink feeding head carried by the lower end of said barrel structure, a multiplicity of concentric cylindrical members connected with said barrel structure, one of said cylindrical members being telescopically slideable with respect to said barrel structure, an air feeding tube extending axially through said barrel structure, a valve at each end of said air feeding tube for controlling the filling and writing operations of said pen, and a friction device engageable with the interior walls of said telescopically slideable member for simultaneously controlling the operation of both of said valves.

ALFRED H. SWAN.
